ATTORNEY

UNITED STATES PATENT OFFICE

ISIDOR HEIDENREICH, OF ST. LOUIS, MISSOURI

SCRATCH SHEET OR PAD HOLDER

Application filed June 6, 1927. Serial No. 196,883.

This invention relates to a certain new and useful improvement in scratch-sheet or pad holders.

My invention has for its chief object the provision of a device of the type stated comprising a base and pad-retaining-means, the latter being of such construction as to automatically adjust itself to continuously hold the pad or sheets upon the base until the consumption thereof.

My invention has for a further object the provision of a device of the type stated that is conveniently usable, which is simple, compact, and durable in form and structure, and which may be inexpensively manufactured.

And with the above and other objects in view, my invention resides in the novel features of form, construction, arrangement, and combination of parts hereinafter described and pointed out in the claims.

In the accompanying drawing,

Figure 1 is a plan view of a scratch-pad holder embodying my invention;

Figure 2 is a fragmental plan view of the holder;

Figure 3 is an end view of the holder;

Figure 4 is a side elevational view of the holder; and

Figure 5 is a sectional view of the holder on approximately the line 5—5, Figure 1.

Referring now more in detail and by reference characters to the drawing, which illustrates a preferred embodiment of my invention, A designates the base of the holder, which is constructed of any suitable preferably stiff or rigid material, such as wood, heavy cardboard, or the like and which is of suitable dimensions and preferably of oblong-rectangular contour.

Constructed preferably of spring-wire or other suitable material to include a bight 1 and preferably right-angularly projecting arms 2, 2, the latter at their free ends 3, 3, being bent to extend for a short distance obliquely inwardly, as seen in Figure 1, is an approximately or substantially U-shape frame B, which is disposed in inverted position upon the upper face of base A and fixed to base A by means of a rivet 4, eyelet, or the like engaging the frame-bight 2 at approxi-

mately the longitudinal center thereof and base A and by rivets, 5, 5, eyelets, or the like engaging the ends 3, 3, of the arms 2, 2, and the base A, all as best seen in Figures 1 and 5.

As so constructed and fixed to base A, the opposite-portions b, b', of the frame B intermediate the rivet or eyelet 4 and the respective rivets or eyelets 5 are yielding and resilient relatively to the base A, and looped and fastened, as at 6, to the one yielding or spring frame-portions b for both, relatively to base A, transversely swingable and longitudinally slidable movement, is a preferably straight edge strip C of dimensions to extend transversely over base A and detachably engage, as by means of a lip or hook 7 formed on the free end thereof, under and with the opposite yielding frame-portion b'. 65

In use and operation, strip C being disengaged from frame-portion b' and swung back, as indicated by dot-and-dash lines in Figure 3, the scratch-sheets D, in connected or pad, or loose and disconnected form, are disposed flatwise upon base A and within the confines of frame B. When the sheets D 75

are so disposed upon base A, frame B naturally lies normally flatwise upon base A. However, as strip C is now reversely swung down upon the sheets D and manually engaged at its hook or lip 7 with the frame-portion b', so

the frame-members b and b' give or yield, as seen in Figure 4, depending, of course, upon the thickness of the pad D. Strip C now extending over and across the sheets D and engaged with frame-portion b', the pad or 85 superposed sheets D is firmly held in writing-receptive position upon base A, the strip C, in co-operation with the yielding frame-portions b and b', continuing so to function and to automatically adjust themselves as the

thickness of the pad or sheets D is reduced during consumption thereof. As so retained upon the base A, the successive sheets D may be endwise removed from under the strip C or torn in selected sections, as may be desired, an operation readily facilitated by the longitudinally slidable and straight-edge strip C, as illustrated in Figure 1. Ruling upon the uppermost sheet D may also readily be effected through use and shifting of the 90 95 100

holding strip C, as illustrated in Figure 2.

Thus, any suitable number of sheets, within the allowable limits of the particular holder, may be neatly and firmly held and retained upon the base A, the frame-portions b and b' giving or yielding not only to accommodate the full pile or number of sheets D, but also and automatically, as they tend to return to normal position as the pile of sheets is reduced in number or thickness, to continue to retain the remaining sheets D as successive sheets of the original pile are consumed.

My new holder is exceedingly efficient in the performance of its intended functions and in the accomplishment of the objects mentioned.

I am aware that changes in the form, construction, arrangement, and combination of the several parts of my new holder may be made and substituted for those herein shown and described without departing from the nature and principle of my invention.

Having thus described my invention, what I claim and desire to secure by Letters Patent is:

1. In a scratch sheet holder, a base for supporting for consecutive use a plurality of sheets in piled superposed relation, a pair of spring-wire strips fixed upon the base and extending lengthwise along the opposite sides of the base and the scratch sheets supported thereupon, and a second strip adapted to extend crosswise the base over said sheets for yieldingly retaining the sheets in total and successively reduced number on the base, the second strip being permanently connected at one end with one of the first strips and being adapted for detachable engagement at its other end with the other of the first strips.
2. In a scratch sheet holder, a base for supporting for consecutive use a plurality of sheets in piled superposed relation, a pair of spring-wire strips fixed upon the base and extending lengthwise along the opposite sides of the base and the scratch sheets supported thereupon, and a second strip adapted to swingably extend crosswise the base over the sheets for yieldingly retaining the sheets in total and successively reduced number on the base, said second strip having hinged connection at one end with one of the first strips and being adapted for detachable engagement at its other end with the other of the first strips.
3. In a scratch sheet holder, a base for supporting for consecutive use a plurality of sheets in piled superposed relation, a pair of spring-wire strips fixed upon the base and extending lengthwise along the opposite sides of the base and the scratch sheets supported thereupon, and a second strip adapted both to swingably extend crosswise the base over the sheets for yieldingly retaining the sheets in total and successively reduced number on the base and for movement as a guide member

longitudinally the base, said second strip having a slideable hinged connection at one end with one of the first strips and having a slideable detachable connection at its other end with the other of the first strips.

4. In a scratch sheet holder, a base for supporting for consecutive use a plurality of sheets in piled superposed relation, a spring-wire U-shaped frame disposed on the upper face of, and fixed centrally at its bight and at the free ends of its arms to the base, said frame having portions extending lengthwise along the opposite sides of the sheets supported on the base, and a strip adapted to swingably extend crosswise the base over the sheets for yieldingly retaining the sheets in total and successively reduced number on the base and for movement as a guide member longitudinally the base, said second strip having a slideable hinged connection at one end with one of the first arms and having a slideable detachable connection at its other end with the other of the first arms.

In testimony whereof, I have signed my name to this specification.

ISIDOR HEIDENREICH.
